UNITED STATES PATENT OFFICE

FRED C. FANTZ, OF WEBSTER GROVES, MISSOURI, ASSIGNOR TO E. A. BENDING, OF CHICAGO, ILLINOIS

COMBINATION OIL AND GAS BURNER

Application filed January 31, 1929. Serial No. 336,390.

My invention relates to the art of combustion, and particularly to burners adapted for receiving and atomizing oil and gas for combustion purposes.

5 My invention has for its principal object, to provide means for thoroughly and completely receiving and breaking up oil, mixing it with steam or air, and finally with gas, before delivering it to the burner, where it is then again mixed with air to provide the necessary oxygen for combustion.

A further object is, to provide a device of 15 this character, whereby the oil may be utilized separately, or the gas may be used separately, or the two may be burned together, all being admitted and mixed with oxygen for combustion purposes, through the same burner tip.

A further object is, to produce a device of 20 this character, whereby fuel will be so thoroughly gasified that the combustion thereof will be substantially complete, and less carbonization will result in deposits, either in the burner body or the ports in the burner 25 tip, thereby providing long life and satisfactory functioning at all times for the burner tips, and not necessitating changes when different fuels (gas and oil) are used.

A further object is, to provide a device 30 whereby the oil used will be so completely torn apart and broken up as to insure a more complete combustion, thereby practically eliminating the clogging and burning off of the burner tip as is customary in most burners.

My invention consists of certain details of construction hereinafter set forth, pointed out in my claims, and illustrated in the accompanying drawings, in which—

40 Fig. 1 is a side elevation of my device installed in a boiler furnace, part of same being broken away and sectioned;

Fig. 2 is a longitudinal cross-section of the burner, taken on line 2—2 in Fig. 1; and

45 Fig. 3 is a cross-section, taken on line 3—3 of Fig. 2, showing valve control.

Similar reference numerals refer to similar parts, throughout the entire description.

50 My device comprises four principal parts, to receive a combination of oil and gas, break

up the particles of oil, thoroughly mix the oil with steam and air, and deliver it through the burner tips, where it mixes with oxygen for combustion purposes. The device itself is principally adapted for use in boilers, 55 stills, furnaces and combustion chambers in general, and is especially designed for and adapted to the burning of poor grade fuel and high gravity oil.

The mixing head 10 which I employ, has an inlet passage 11 to receive the oil to be converted into a combustible vapor, a passage 12 to receive the steam or air to be injected into the mixing chamber to assist in breaking up and vaporizing the oil, and a passage 13 to receive gas to be delivered to an expansion or gasifying chamber where it mixes with the vaporized oil being projected from the mixing chamber. The passages 11 and 12 are, as shown in the illustration accompanying this specification, substantially parallel, spaced apart, and extend into the mixing head 10 beyond the center thereof. A nozzle 14, provided with a port 15, is connected with, and to, the oil passage 11. In the structure 70 shown in the drawings, this nozzle 14 projects through the steam passage 12, and through a screw-threaded orifice 16 in the wall surrounding the said steam passage 12. A cylinder 17 is secured in the wall surrounding the screw-threaded orifice 16, the cylinder 17 receiving at its lower end the nozzle 14 which, obviously, is centrally located, concentrically, within the end of said cylinder 17. The cylinder 17 is open at both 75 ends, and at its inner end communicates with the steam or air passage 12, thus providing for air received through the passage 12 entering into the cylinder 17. A corrugated spiral element 18, its walls contacting the inner wall of the cylinder 17, is mounted within said cylinder 17. A cylinder 19 surrounds, and extends outwardly beyond, the cylinder 17, and is seated in the mixing head 10 so that the lower end of said cylinder 19 opens 80 into the gas passage 13. Obviously, the cylinder 19 is evenly spaced, concentrically, from the outer wall of the cylinder 17, and in the outer end of the cylinder 17 I have 85 mounted a burner tip 20.

The burner, the functioning of which will be hereinafter explained, is designed to project into a combustion space 21, and in order to provide for proper combustion, by the delivery to the burner tip 20 of the necessary oxygen, I have mounted in the end of the combustion space 21 my air-delivering device, which functions in connection with the burner which has been hereinbefore described. This air-delivering device, which may be termed an air register, consists of a body portion 22, which completely fits within the opening in the combustion chamber 21 through which the burner top 20 projects. This body portion 22 has an opening 23, or a plurality of openings if desired, to the outside air, to receive air from the outside of the combustion chamber 21 and convey it to the burner tip 20.

My purpose is, so to deliver this outside air to the burner tip 20 as to provide for complete combustion of the gas going therethrough, and to that end I provide vanes 24, around which the air coming through the openings 23 must pass, these vanes 24 imparting a whirling motion to the air. This whirling air or oxygen is delivered through or around openings in a grid 25, passes over the burner tip 20, and provides complete and satisfactory delivery of oxygen over the burner tip 20, for combustion. My air register is so constructed that it has an adjustable element 26, which may be positioned through the medium of traveling screw 27, operated by gear 28 seated in part 29 and manipulated by the operator, to enlarge or reduce the size of the air passages 23 according to the desire or need of the operator.

In practical operation, oil is delivered through the passage 11 and nozzle 14 into the cylinder 17. Obviously, this delivery is under the desired pressure. Steam or air, also under pressure, is at the same time delivered to the cylinder 17 through the passage 12, and mixes with the incoming oil. The incoming oil, mixed with the steam or air, is thrown against the corrugated spiral 18 which, by reason of its spiral formation, imparts a whirling motion to the oil and steam, throwing it against the inner wall of the cylinder 17, which operates to break up the particles of oil. In addition to this, the oil particles are continually being thrown against the corrugations in this spiral element 18, which further operates to break up the oil particles. The result of this is, that the oil, in passing through the cylinder 17, which I term my mixing chamber, is completely and entirely broken up and all solids atomized, so that the resultant vapor which is projected from the outer end of the cylinder 17 is free from solids and particles, residue and the like. As this vapor is projected from the end of the cylinder 17, it enters the cylinder 19 which, as hereinbefore described, is connect-

ed with the gas passage 13. When the oil and the steam are being delivered to the mixing chamber 17, as hereinbefore described, the two fluids—the natural gas coming through the passage 13, and the vaporized oil and steam coming through the mixing cylinder 17—are completely mixed in the end of the cylinder 19 before being projected through the ports in the burner tip 20. This end of the cylinder 19, wherein the natural gas and the vaporized oil and steam are mixed, I have termed my expansion chamber 30.

As the gas thus formed by vaporizing the oil and steam and mixing it with the gas, is thrust out from the ports in the burner tip 20, it is there met by the whirling oxygen which is coming in through the orifices 23 in the air register, and this provides for complete and satisfactory combustion.

Having thus described my invention, what I claim, and desire to secure by Letters Patent of the United States, is:

1. A burner for fuel composed of gas and vaporized oil and air or steam, comprising a mixing head with passages therein to receive the gas, the oil, and the steam or air; a cylinder seated in the mixing head to receive the incoming oil and incoming steam or air; a spiral element secured in said cylinder; a second cylinder, also seated in the mixing head, and concentrically spaced from and surrounding the first cylinder, to receive the incoming gas; and a burner tip in the end of said second cylinder.

2. A burner for fuel composed of gas and vaporized oil and air or steam, comprising a mixing head with passages therein to receive the gas, the oil, and the steam or air; a cylinder seated in the mixing head to receive the incoming oil and incoming steam or air; a corrugated spiral element secured in said cylinder; a second cylinder, also seated in the mixing head, and concentrically spaced from and surrounding the first cylinder, to receive the incoming gas; and a burner tip in the end of said second cylinder.

3. A burner for fuel composed of gas and vaporized oil and air or steam, comprising a mixing head with passages therein to receive the gas, the oil, and the steam or air; a cylinder seated in the mixing head to receive the incoming oil and incoming steam or air; a second cylinder, also seated in the mixing head, and concentrically spaced from and surrounding the first cylinder, to receive the incoming gas; a burner tip in the end of said second cylinder; and means to deliver air over the end of the burner tip.

4. A burner for fuel composed of gas and vaporized oil and air or steam, comprising a mixing head with passages therein to receive the gas, the oil, and the steam or air; a cylinder seated in the mixing head to receive the incoming oil and incoming steam or air; a second cylinder, also seated in the mix-

ing head, and concentrically spaced from and surrounding the first cylinder, to receive the incoming gas; a burner tip in the end of said second cylinder; an air register surrounding the said second cylinder; and a spiral element in said air register to impart a whirling motion to the air delivered out over the burner tip.

5. A burner for fuel composed of gas and vaporized oil and air or steam, comprising a mixing head with passages therein to receive the gas, the oil, and the steam or air; a cylinder seated in the mixing head to receive the incoming oil and incoming steam or air; a spiral element secured in said cylinder; a second cylinder, also seated in the mixing head, and spaced from and surrounding the first cylinder, to receive the incoming gas; a burner tip in the end of said second cylinder; and means to deliver air over the end of the burner tip.

6. A burner for fuel composed of gas and vaporized oil and air or steam, comprising a mixing head with passages therein to receive the gas, the oil, and the steam or air; a cylinder seated in the mixing head to receive the incoming oil and incoming steam or air; a spiral element secured in said cylinder; a second cylinder, also seated in the mixing head, and spaced from and surrounding the first cylinder, to receive the incoming gas; a burner tip in the end of said second cylinder; an air register surrounding the said second cylinder; and a spiral element in said air register to impart a whirling motion to the air delivered out over the burner tip.
